UNITED STATES PATENT OFFICE.

JULIUS T. TURNER, OF GRAFTON, MICHIGAN.

IMPROVEMENT IN HORSE-COLLARS.

Specification forming part of Letters Patent No. 222,964, dated December 23, 1879; application filed August 25, 1879.

To all whom it may concern:

Be it known that I, JULIUS T. TURNER, of Grafton, in the county of Monroe and State of Michigan, have invented a new and useful Improvement in Horse-Collars, of which the following is a specification.

I have improved that class of collars which are made to open at the throat or lower end.

My object is to render the collar strong and durable at the points of greatest strain and wear. For this purpose I incase the divided or throat parts with a metal casing of two sections, each having a double tubular-formed part, closed at the end and adapted to be driven on and over the lower divided ends of both the pad and the roll part a sufficient distance to form a firm and bracing case for these collar parts, with the ends of the separate cases joining. That part of the casing which receives the roll is formed with a shield, extending to a point at which the draft-chain connection is made with the hames, for the purpose of protecting that part of the roll from being cut or worn out by the chain or strap which connects the hames with the pole; also, to hold the latter up and maintain the hame-receiving crease at this point to its form and depth, and in this respect serving an important advantage in keeping the hames securely within the roll-crease when the team is backing. This shield part envelopes enough of the roll part to allow it to be secured thereto by through-rivets, while the tubular parts are also secured both to the roll and to the pad parts by through-rivets. This mode of fastening gives a very firm attachment for the casing to the collar. One of these tubular parts has dowel-pins formed upon its closed end, and the closed end of the other tubular part has perforations to receive the dowel-pins, which are so arranged that one will lock the roll ends and the other the pad ends, to prevent all twisting and shifting, and keeping the collar ends from working back and forth at each step of the team.

A clasp may be used to hold the ends of the collar together; but this fastening is not absolutely necessary, as the hames keep its dowel-connection secure.

Each tubular part and shield is formed as an entirety, bracing not only the divided col-

lar ends, but the roll part, to the point of draft, keeping those parts of the collar in shape and preventing it from closing with irregular or irritating action upon the horse's neck.

A collar open at the throat is not new; and I am also aware that metal caps have been secured by screws over the ends of such open collar, and held together by spring-latches, such caps being secured by interior devices fastened by stitching to the divided ends of the collar; and that a wooden collar, open at the neck, has been provided with a dowel-fastening and riveted plates, with eyes for fastening the ends together with a pin, like a hinge and its pintle-pin; and that a plate has been applied to a non-divided throat end of the collar, conforming to its shape, extending upward along the sides and held in place by clasp-ears, which lap the lower middle part of the collar, for the purpose of bracing and holding the collar to its form; but in this case the collar opens at the top only, and has the usual buckle fastening.

My improvement has important advantages over these constructions, whereby an open-throat collar is made more effective, durable, and desirable.

Referring to the accompanying drawings, Figure 1 represents a view, in perspective, of a horse-collar embracing my invention; Fig. 2, the metal tubular bracing casing for the divided throat-ends of the collar; Fig. 3, a section on the line z z of Fig. 2; and Fig. 4, a section through the tubular casing.

My improvement is primarily designed for use with horse-collars open only at the throat or lower end; but it may be applied and used on collars adapted to buckle at the top. If used, however, on this class of collars the upper end must be kept tightly buckled; but in collars so made the buckling-straps tear out or become broken, and the frequent springing open of the collar, in applying and removing it, breaks it at the lower end and puts it out of shape, causing it to irritate and close harshly upon the horse's neck and shoulders, and on this account the opening of the collar at the lower end is preferable and best.

To obtain the best results in the use of such collar, I provide each of its lower divided parts

with a tubular-formed metal casing—one part, A, of which receives the pad part B for about two inches, and the other part, C, of said casing receives the roll part D about the same or a little greater distance, these tubular parts having a regular inner-side surface, while the outer sides conform to the roll-crease. Each of these tubular parts has a closed end, E, which, when joined, form a close bearing in the middle of the collar-bend.

The tubular roll part of each casing has formed with it a shield, F, extending up to a point where the draft-connection is made with the hames, and is made to cover the outer part of the roll sufficiently to be secured thereto by rivets *a*, which pass through said shield and roll, and are riveted at each end, two or more such rivets making the connection secure. The closed end of one of these casings has solid dowel-pins *b b* formed thereon, one projecting from the pad part and the other from the roll part, and adapted to enter corresponding holes in the closed end of the other casing. These tubular casings are driven over the divided ends of the collar, binding them firmly, and are secured by rivets *c c*, one passing through the pad part and the other through the roll part, making a durable and firm bracing to that part of the collar which sustains the greatest strain and wear, and giving a regular bearing upon the horse's neck and shoulders, while the shield protects that part of the roll from the cutting and wearing action of the chain or strap which connects the hames with the tongue. The dowel-connections pre-

vent all twisting of the collar at the joining, as they lock both the pad and the roll parts together. A clasp may be used to maintain a close joint, but when the hames are applied it is made secure. The clasp may be a link, *d*, fastened by a riveted eye, *e*, in one part, and hooking over a pin, *f*, in the other part, and secured by a key, and the clasp may be placed on the roll part, or may be placed so as to fasten in the crease.

The tubular casings may be cast or formed in any suitable manner of thin metal, and sold to the trade in different sizes, and complete for use either for new collars or old ones. When the collar is worn out, the casings may be removed by drawing the rivets, and applied to another collar.

I claim—

1. In a horse-collar open at the lower end, the combination therewith of the tubular metallic casings, formed substantially as herein set forth, and provided with shield-extensions F for the roll parts D, secured thereto by through-rivets, substantially as herein set forth.

2. As an improved manufacture, metal horse-collar casings having the tubular pad and roll parts, the shield extensions for the latter, inner-side regular surfaces, closed ends, and dowel-connections, substantially as and for the purpose herein set forth.

JULIUS T. TURNER.
